COMBINED FILTER AND PUMP

David Greene. 20 Ferris Drive,
West Orange, N.J. 07032

Filed May 1, 1969, Ser. No. 16,976

Term of patent 14 years

Int. Cl. D23—01; D15—02
U.S. Cl. D23—4

FIG. 1

FIG. 2

FIG. 3

FIG. 4

FIG. 5

The handles on the smaller suspended casing are shown in an alternate position in FIGURES 3 and 4.

I claim:

The ornamental design for a combined filter and pump, as shown and described.
